UNITED STATES PATENT OFFICE.

MAX RUTH, OF JERSEY CITY, NEW JERSEY.

SAW-HANDLE.

1,277,131.

Specification of Letters Patent. Patented Aug. 27, 1918.

Application filed June 25, 1917. Serial No. 176,707.

To all whom it may concern:

Be it known that I, MAX RUTH, a citizen of the United States, and a resident of Jersey City, in the county of Hudson and State 5 of New Jersey, have invented a new and Improved Saw-Handle, of which the following is a full, clear, and exact description.

This invention relates to saws and deals more particularly with an adjustable handle 10 whereby the handle can be set at ninety degrees to the plane of the blade or in the same plane with the latter.

The invention has for its general objects to improve the construction of handles of 15 this character so as to be comparatively simple and inexpensive to manufacture, reliable and efficient in use, and so designed as to be easily and quickly adjusted.

A more specific object of the invention is 20 the provision of a novel form of hinge between the handle and the plate or leaf to which the blade is riveted, such hinge having yieldingly connected members for permitting the interengaging of clutch teeth on 25 the eyes of the hinge, the pintle of the hinge being in the form of a bolt which is tightened to cause the teeth to be firmly interlocked.

With such objects in view, and others 30 which will appear as the description proceeds, the invention comprises various novel features of construction and arrangement of parts which will be set forth with particularity in the following description and 35 claims appended hereto.

In the accompanying drawing, which 40 illustrates one embodiment of the invention and wherein similar characters of reference indicate corresponding parts in all the views,

Figure 1 is a perspective view of the saw with the handle adjusted to a position at right-angles to the plane of the blade;

Fig. 2 is a plan view with a portion of the 45 handle broken away to illustrate the details of construction; and

Fig. 3 is a section on the line 3—3, Fig. 2. Referring to the drawing, A designates an ordinary saw blade and B the handle 50 attached to the blade. This handle comprises a base plate or attaching section 1, a hinge 2 and a handle section 3. The section 1 is fastened by rivets 4 to the blade and it is formed with a central eye or apertured 55 ear 5. The handle section 3 is composed of

a grip member 6 and yieldingly connected members 7 which terminate in apertured eyes 8 disposed at opposite sides of the central hinge eye 5. A bolt 9 having a wing nut 10 passes through the apertured eyes to 60 constitute a pintle and a clamping means for causing the eyes to rigidly engage each other. To insure a positive engagement of the eyes they are provided with interlocking teeth 11 on their meeting faces. The members 7 normally spring apart so that the teeth 11 will have yielding engagement for enabling the handle to be adjusted to the position shown in Fig. 1 or to that shown in Fig. 2, and after so adjusted the bolt 70 is tightened so as to hold the handle section rigid with respect to the saw blade. The grip member 6 has a recess 12 in which the members 7 and the thin yielding connecting portion 13 are disposed, and fasteners 14 75 pass through the grip member 6 and the connected members 7 so as to hold these parts yieldingly together. Before the handle is adjusted the wing nut 10 is slightly unscrewed so that the members can move 80 outwardly from each other by the cam action of the interlocking teeth 11 when the handle is turned, and after the handle is adjusted to the right position the wing nut 10 is again tightened.

From the foregoing description taken in connection with the accompanying drawing, the advantages of the construction and method of operation will be readily understood by those skilled in the art to which 90 the invention appertains, and while I have described the principle of operation, together with the device which I now consider to be the best embodiment thereof, I desire to have it understood that the device shown 95 is merely illustrative and that such changes may be made when desired as fall within the scope of the appended claims.

Having thus described my invention, I claim as new and desire to secure by Letters 100 Patent:

1. The combination of a saw blade having a hinge eye, a handle having a channel, a U-shaped element composed of side members and a cross bar, the cross bar being resilient and set in the channel of the handle, 105 said side members being provided with eyes alining with the eye on the blade, a bolt passing through the eyes for connecting the handle with the blade, and interengaging 110

2
teeth between the eyes for holding the handle in the plane of the blade or at an angle thereto.

2. The combination of a saw blade having 5 an eye, a handle formed with a channel, spaced members projecting from the handle, resilient connecting means located in the channel for uniting the members, eyes on

the members, a bolt passing through the eyes on the blade and the members, and means for 10 clamping the eyes together to hold the handle in different positions of adjustment.

MAX RUTH.
